UNITED STATES PATENT OFFICE.

STEPHEN S. S. KENNEDY, OF PONTIAC, MICHIGAN.

GRATE.

Application filed July 8, 1925. Serial No. 42,225.

The present invention relates to grates and aims to provide a novel and improved device of this character which is more especially adapted for use in burning bituminous or soft coal, said grate being so constructed that coal burned thereon will give off an intense heat and practically all combustible particles of the coal will be ignited, whereby the utilization of coal is minimized 10 to a great extent.

Another object of the invention is to provide a grate having a series of air chambers arranged to extend upwardly in a fire box for receiving air therein under pressure, 15 said chambers having communication to the fire box through openings at the sides of the chambers, whereby the air under pressure from the various chambers will be directed in the fire box more in horizontal direction 20 than a vertical direction, thus eliminating to a great extent combustible particles of coal being blasted to and pass the boiler before being properly ignited, which would reduce the efficiency of the coal consumed.

25 A further object of the invention is the provision of a grate constructed of a series of units, each consisting of a raised portion which is reinforced at a certain point for preventing sagging when the units are subjected to a high temperature, and a flange 30 at the base of the raised portion upon which are placed fire bricks for retaining the units in place.

It is also an object of the invention to provide a grate of the kind indicated, which is simple and substantial in construction, which can be manufactured economically, and which will be thoroughly efficient and practical in use.

40 With the foregoing and other objects in view, which will be apparent as the description proceeds, the invention resides in the construction and arrangement of parts, as hereinafter described and claimed, it being 45 understood that changes can be made within the scope of what is claimed, without departing from the spirit of the invention.

The invention is illustrated in the accompanying drawings, wherein:

50 Figure 1 is a vertical cross section of a furnace showing my improved grate applied thereto,

Figure 2 is a horizontal section taken on line 2-2 of Figure 1;

55 Figure 3 is a top plan of one of the grate units,

Figure 4 is a fragmentary side elevation of the same, showing a portion thereof in section,

Figure 5 is an end elevation of a grate 60 section, and

Figure 6 is a cross section of a grate section taken on line 6-6 of Figure 4.

Referring to the drawings by numerals, 10 designates a furnace having side walls 11 which support a boiler 12. Arranged at the front of the furnace is a pair of doors 13 for permitting access to the fire box 14. In carrying out my invention, the numeral 15 indicates a floor for the furnace which is 70 constructed of fire bricks and fire clay. Supported on the floor 15 is a series of metallic grate members 16, which are semi-cylindrical so as to provide raised portions 17. At the lower edges of the semi-cylindrical 75 sections are provided continuous flanges 18 which rest upon the floor 15, said flanges having placed thereon fire bricks 19 which are held in place by fire clay for retaining said semi-cylindrical sections in their proper 80 positions.

The semi-cylindrical sections 17 have their opposite ends closed, as at 20, so as to form an air chamber in each section, the floor 15 serving as a means for closing the 85 bottom of said section. The semi-cylindrical sections are gradually increased in thickness as they extend from the flanges 18 so as to provide a relatively thick wall at the uppermost portions thereof, as indicated 90 by the numeral 21. Arranged in the opposite sides of the semi-cylindrical sections are rows of openings 22 for permitting the air in the chambers to escape into the fire box. It will be noted that there are two rows of 95 openings on each side of the semi-cylindrical sections and that each opening is gradually reduced in size as it extends outwardly so as to give a spraying effect when the air is forced therethrough under pressure. By 100 providing the openings to the sides of the cylindrical members, the air from one chamber is directed towards the air from another chamber, thus giving a cross fire effect so as to thoroughly burn all combustible matter 105 in the fire box and for eliminating the blasting of the fuel from the fire box.

In order that air may be supplied to the chambers formed by the semi-cylindrical sections, I have provided a compressed air tank 110 23 which has communication through a main supply pipe 24 and branch supply

pipes 25 to the chambers. The branch pipes 25 extend through the forward portion of the floor 15 and communicate with the chambers at the lower forward ends of the 5 semi-cylindrical members. In each of the branch pipes 25 is provided a valve 26 for regulating the flow of air to the chambers which will control the burning of the fire in the fire box. Extending to the compressed 10 air tank 23 is a pipe 27 having a cut-off valve 28 therein, said pipe leading from an air pump (not shown).

In operation, the fuel is placed in the fire box through the doors 13 in the forward 15 end of the furnace and upon the upper surfaces of the semi-cylindrical members 17, which together with the fire bricks 19 support the fuel in the fire box. The air under 20 pressure from the tank 23 is forced through the tapered openings 22 for causing a draft in order that the fuel may burn, the fire being regulated by the valves 26 which control 25 the flow of air. It can thus be seen that the small particles of coal placed in the fire box will not be permitted to drop through the grate as in furnaces now in use, and that the loss of coal due to falling through the grate and being blasted out of the fur-

nace is eliminated, thus minimizing the consumption of fuel. As the semi-cylindrical 30 sections are of much greater thickness at their uppermost portions, it can also be seen that when the walls of the sections are highly heated due to the fire thereon, the same 35 will not sag or become distorted due to the weight of coal pressing thereupon.

Having thus described my invention, what I claim as new is:

In a grate structure a series of hollow bodies closed at their ends, said bodies being arched transversely and the bodies being provided at their edges with outstanding flanges which completely circumscribe the same, a support holding the flanges in a common plane and substantially abutting each other, fire resisting elements set upon the flanges and extending in series completely around the bodies, the opposite side walls of the bodies being provided with openings 40 located above the upper surfaces of the fire 45 resisting elements and below the top of the arched walls of the bodies.

In testimony whereof, I have affixed my signature.

STEPHEN S. S. KENNEDY.
